(57) **CLAIM**

The ornamental design for a vehicle exterior, as shown and described.

DESCRIPTION

FIG. 1 is a front perspective view of a vehicle exterior showing my new design;

FIG. 2 is a top plan view thereof;

FIG. 3 is a front elevational view thereof shown with the headlamps in an open position;

FIG. 4 is a side elevational view of one side thereof; the opposite side being a mirror image thereof;

FIG. 5 is a rear elevational view thereof;

FIG. 6 is a front elevational view similar to FIG. 3 shown with the headlamps in a closed position; and,

FIG. 7 is a rear perspective view thereof.

The broken line showings of the wheels, tires, front grille elements and the elements in the rear vertical element are for illustrative purposes only and form no part of the claimed design.
